UNITED STATES PATENT OFFICE.

CHARLES A. STUART, OF KENOSHA, WISCONSIN, ASSIGNOR TO SIMMONS COMPANY, OF NEW YORK, N. Y., A CORPORATION OF DELAWARE.

DESIGN FOR AN END FRAME FOR BEDSTEADS.

Application filed March 20, 1929. Serial No. 30,545. Term of patent 7 years.

To all whom it may concern:

Be it known that I, CHARLES A. STUART, a citizen of the United States, and a resident of the city of Kenosha, county of Kenosha, and State of Wisconsin, have invented a new, original, and ornamental Design for End Frame for Bedsteads, of which the following is a specification, reference being had to the

accompanying drawing, forming part thereof.

The figure is a perspective view of a bedstead end frame showing my new design.

I claim:

The ornamental design for an end frame for bedsteads as shown.

CHARLES A. STUART.
